UNITED STATES PATENT OFFICE.

WILLIAM MASON, OF NEW HAVEN, CONNECTICUT, ASSIGNOR TO THE
WINCHESTER REPEATING ARMS COMPANY, OF SAME PLACE.

AUTOMATIC MACHINE FOR WADDING AND CUPPING PAPER CARTRIDGE-SHELLS.

SPECIFICATION forming part of Letters Patent No. 588,801, dated August 24, 1897.

Application filed June 26, 1895. Serial No. 554,067. (No model.)

To all whom it may concern:

Be it known that I, WILLIAM MASON, of New Haven, in the county of New Haven and State of Connecticut, have invented a new Improvement in Automatic Machines for Wadding and Cupping Paper Cartridge-Shells; and I do hereby declare the following, when taken in connection with the accompanying drawings and the letters of reference marked thereon, to be a full, clear, and exact description of the same, and which said drawings constitute part of this specification, and represent, in—

Figure 1, a view of one form which a machine constructed in accordance with my invention may assume, the wadding mechanism being shown in side elevation and the cupping mechanism being shown in front elevation; Fig. 2, a view with the wadding mechanism shown in front elevation and the cupping mechanism shown in side elevation; Fig. 3, a plan view of the machine; Fig. 4, a partial view of the machine in rear elevation, with particular reference to showing the driving connections of the feed-rolls and knives; Fig. 5, an enlarged view, in vertical central section, through one of the wad-winding spindles and the parts immediately connected therewith; Fig. 5^a, a broken reverse plan view of the spindle, together with its annular die and knife, and showing a wound wad in the die; Fig. 5^b, a detached plan view showing one of the stop-cams; Fig. 5^c, a view in transverse section on the line *a b* of Fig. 5; Fig. 5^d, a view in transverse section on the line *c d* of the same figure; Fig. 6, a partial plan view of the wadding mechanism, with particular reference to showing the operating connections of the feed-rolls; Fig. 7, a view, partly in plan and partly in transverse section, also showing the operating connections of the feed-rolls; Fig. 8, a view in vertical section through the movable and yielding feed-roll *F'* on the line *e f* of Fig. 7; Fig. 9, a partial view, in front elevation, of the wadding mechanism, with particular reference to showing the plunger-head and the connection of the same to the plunger; Fig. 10, a view, partly in plan and partly in section, of the wadding mechanism, with particular reference to showing the knives which cut off the

paper strips; Fig. 11, a detached plan view of the stop-cams of the wad-winding spindles, the stop-fingers which coöperate with the said cams, the arms carrying those fingers, and the rock-shaft carrying the arms; Fig. 11^a, a view of the same parts in front elevation; Fig. 11^b, a detached view of the operating-finger which is mounted on the rock-shaft; Fig. 11^c, a detached view of one of the stop-fingers; Fig. 12, a broken view, in vertical section, of the lower end of the chute of the assembling or cupping machine, showing also a portion of the dial of the feeding mechanism; Fig. 12^a, a view, partly in section and partly in front elevation, of the cup-holding fingers of the said mechanism; Fig. 13, a detached plan view of the said fingers.

My invention relates to an improvement in automatic machines for making paper-shell cartridges, and is designed to wind wads and introduce them into the paper tubes and then to apply sheet-metal cups to the wadded ends of the tubes, the object being to avoid handling the tubes after they have been wadded and before they are cupped, whereby economy of time and labor is secured, and to produce a machine having a great capacity for superior work.

With these ends in view my invention consists in the combination, in an automatic wadding and cupping machine, with a wadding mechanism, of an assembling or cupping mechanism and a feeding mechanism arranged to present empty paper tubes to the wadding mechanism in position to receive the wads produced thereby and then to present the wadded tubes to the assembling or cupping mechanism in position to have cups applied to their wadded ends, whereby one feeding mechanism suffices for the feeding of one wadding mechanism and also for the feeding of one cupping mechanism.

My invention further consists in certain details of construction and combinations of parts, as will be hereinafter described, and pointed out in the claims.

In carrying out my invention I prefer to employ a wadding mechanism constructed on the principle of that disclosed in United States Patent No. 237,605, granted February 8, 1881, to George P. Salisbury and assigned

to the Winchester Repeating Arms Company. The machine chosen for illustration has a double wadding mechanism, or two wadding mechanisms, functionally independent of each other, but organized together. I do not, however, limit myself to the employment of a wadding mechanism of the character described nor to the employment of a double wadding mechanism.

For the purposes of this description it will be sufficient to describe one of the wadding mechanisms, the same letters of reference being generally applied to both, except where details may vary and where it becomes necessary to repeatedly refer to corresponding parts.

Each wadding mechanism has a vertically-arranged wad-winding-spindle A, having a vertical slot A' formed in its lower end, which is reduced in diameter, as at A². A fixed annular die B, corresponding in internal diameter to the external diameter of the wads to be produced and mounted in fixed position in the frame C of the wadding mechanism, surrounds the reduced and slotted lower end of the spindle, as clearly shown in Fig. 5. This die has a vertical slot B' extending diametrically through its lower end, as clearly shown in Fig. 5^a, and the purpose of which will appear later on. A plunger D, having a central opening D', through which the spindle A passes, is located within the said annular die, to the internal diameter of which its external diameter corresponds, the function of this plunger being to strip the wads wound upon the slotted end of the spindle therefrom and to force them out of the die into the paper tubes E, which at the proper time are presented under the die by the feeding mechanism, to be described later on. The lower end of this plunger has formed in it a vertical slot d, extending diametrically through it, as seen in Fig. 5^d. The upper end of the plunger is screw-threaded and extends upward through a plunger-head D², in which it is adjustably secured by means of two jam-nuts D³ D³, which provide for raising or lowering it in the plunger-head, as may be required.

The wad-winding spindle A is provided at a point above the upper end of the plunger with a grooved wad-winding friction-pulley A³, rigidly secured to it and receiving a round friction - belt A⁴, by means of which the spindle is driven and which slips upon the pulley when the spindle is locked against rotation. The said pulley is constructed with an upwardly-extending hub A^{3a}, which has bearing in a portion of the frame C aforesaid. At its extreme upper end the spindle is furnished with a rigidly-attached stop-cam A⁵, having two oppositely-located stop-shoulders a a, each adapted to be engaged by one of two stop-fingers A⁶ A⁶, the other of which co-acts with the corresponding stop-cam of the other wad-winding spindle. By reference to Fig. 3 it will be seen that the upper ends of both spindles have bearing in the frame C,

and by reference to Fig. 9 that the plungers D of both spindles are mounted in the said plunger-head D², which operates them simultaneously. Wad-paper is supplied to the machine, as required, in the form of long coils A⁷ A⁷, Fig. 3, which are placed in paper-holders A⁸ A⁸ of any approved construction. Two pairs of feed-rolls F and F' and F² and F³ are employed for feeding the paper to the slotted lower ends of the spindles. These rolls, though driven continuously, are operated only intermittently to grip the paper strip and feed the same forward through the slots of the dies, plungers, and spindles, immediately after which they let go of the paper, which is then drawn from the coils by the spindles themselves, which grip it as soon as they begin to wind it upon itself. The rolls F and F² of the respective pairs are secured to the lower ends of vertically-arranged feed-roll driving-shafts F⁴ F⁵, Fig. 4, each furnished at its upper end with a grooved pulley F⁶ F⁶, the two pulleys receiving a round belt F⁷. The shaft F⁵ is also furnished with a grooved pulley F⁸, receiving a driving-belt F⁹, also passing over grooved guide-pulleys F¹⁰ F¹⁰ and over a grooved driving-pulley F¹¹, mounted upon the driven shaft G of the machine. Each of the feed-shafts F⁴ and F⁵ is also furnished with a small pinion F¹², meshing into a corresponding pinion F¹³, the two pinions F¹³ being attached to the upper ends of the feed-roll driven shafts F¹⁴ F¹⁴, to the lower ends of which the rolls F' and F³ are secured. The said shafts F¹⁴ F¹⁴ have bearing in oscillating eccentric bushings F¹⁵ F¹⁶, mounted in portions of the frame C. These bushings are cylindrical in cross-section, but the passages formed in them for the reception of the driven shafts F¹⁴ F¹⁴ are eccentric to their centers, whereby as the bushings are oscillated the said driven shafts and the rolls F' and F³ carried by them are moved toward and away from the rolls F and F², which are fixed in position, but the movement of the shafts F¹⁴ F¹⁴ never disengages the leaves of the pinions F¹² F¹², so that the rolls are driven continuously, though the feeding action is only intermittent. For the lateral oscillation of these two shafts F¹⁴ F¹⁴, I mount upon the driven shaft G a feed-cam F¹⁷, which coacts with an antifriction-roll F¹⁸, mounted in the rearwardly-projecting arm of a vertically-arranged oscillating lever F¹⁹, provided at its upper end with a forwardly-extending pivotal yoke F²⁰, connected with the rear end of a lever f, the forward end of which is pivotally connected with the outer end of a crank-arm f', clamped upon a hub f², formed at the lower end of the eccentric bushing F¹⁵, the upper end of which is constructed with a similar hub f³, upon which is clamped a crank-arm f⁴, with the outer end of which the curved end of a horizontally-arranged coupling-bar f⁵ is connected, the opposite end of the said bar being pivotally connected with a crank-arm f⁶, clamped upon a corresponding hub formed at the up-

per end of the eccentric bushing F^{16} of the other wad-winding mechanism. It will be readily understood from the foregoing that when the feed-cam F^{17} strikes the antifriction-roll F^{18} both of the eccentric bushings F^{15} and F^{16} will be oscillated, with the effect of moving the driven feed-shafts $F^{14} F^{14}$ toward the driving feed-shafts F^4 and F^5 , whereby also the feed-rolls F' and F^3 will be moved toward their fellows, so as to grip the paper, and as both rolls are continuously rotated the paper will be immediately shot forward through the slots in the lower ends of the dies, plungers, and wad-winding spindles. Then just as soon as the feed-cam F^{17} clears the antifriction-roll F^{18} the spring f^7 , Fig. 1, connected with the upper end of the lever F^{19} , will retract the same and through the connections thereof with the eccentric bushings oscillate the same in the opposite direction, whereby the feed-rolls F' and F^3 will be moved away from their fellows and their grip upon the paper relieved, after which the paper will be drawn between them without interference from them by the winding action of the wad-winding spindles. In order to provide for compensating for variations in the thickness of the wad-paper, I prefer to reduce the lower ends of the driven feed-roll shafts $F^{14} F^{14}$, as shown in Fig. 8, where the said shafts are shown to be reduced in diameter, as at f^8 , sufficiently to permit them to yield to permit the paper to pass between the rolls in case it should run thicker than the gage of paper to which the machine is set.

The extreme lower ends of the reduced portions $f^8 f^8$ of the shafts $F^{14} F^{14}$ are still further reduced in diameter for the formation of shoulders against which the feed-rolls F' and F^3 are forced by the nuts applied to the extreme lower ends of the shafts and bearing against the under faces of the said rolls. By reducing the lower end of the feed-roll shafts as described the said ends of the shafts are made sufficiently elastic to spring under extraordinary conditions of pressure. It will be understood, of course, that the shafts are made stiff enough so that they will not be sprung as long as the paper runs uniform in thickness, the shafts then operating as though not reduced and as though perfectly rigid. Should, however, the paper run thicker than gage, the reduced ends of the shafts will spring just enough to allow the rolls to sufficiently separate to permit the thickened portions of the paper to pass between them, whereby the fouling of the machine or the placing of undue strain upon it is avoided. It is important to make this provision for the reason that although great care may be taken in procuring the paper it will sometimes run unevenly as to gage.

Two reciprocating knives $H H$ are employed for cutting off the wound wads from the strips after the wads have been completed and just before they are forced out of the fixed annular dies $B B$ into the paper tubes E by the

plungers $D D$. These knives, Fig. 10, play back and forth upon the flattened surfaces $B^2 B^2$ formed upon the outer faces of the dies and across the diametric slots B' thereof. The said knives are operated simultaneously from the driven shaft G by means of a knife-cam H' , mounted thereupon and coacting with an antifriction-roll H^2 , journaled upon the rearwardly-projecting arm of a vertically-arranged oscillating lever H^3 , provided at its upward end with a forwardly-extending pivotal yoke H^4 , which is connected with the rear end of a link H^6 , the forward end of which is connected with the arm H^7 of a bell-crank lever, the arm H^8 of which has two links H^9 and H^{10} , the outer ends of which are pivotally connected with knife-holders $H^{11} H^{11}$, respectively carrying the knives $H H$ and mounted upon sliding blocks $H^{12} H^{12}$. When the knives are actuated by means of the knife-cam H' , they move forward and cut the paper strips off, and are retracted as soon as the cam H' passes the antifriction-roll H^2 by means of a spring H^{13} , connected with the oscillating lever H^3 . Guides or chutes $H^{14} H^{14}$, Fig. 10, are interposed between the respective pairs of feed-rolls and the respective annular dies, being arranged in the paths in which the paper is fed and in line with the slots in the dies. These guides are secured to pivotal arms $H^{15} H^{15}$, each of which is furnished with a spring $H^{16} H^{16}$, which permit the guides to be pushed out of the way by the knives when the same come forward to cut off the paper and which restore the guides to proper position for guiding the paper immediately after the knives have been retracted. I do not limit myself to these paper-guides, for they may assume a variety of forms.

The plunger-head D^2 , Fig. 9, which carries the two plungers D , is operated by means of a plunger-lever D^4 , the forward end of which it receives. The rear end of this lever carries an antifriction-roller D^5 , which travels in a cam-groove D^6 , formed in one face of the plunger-cam D^7 , mounted on the driven shaft G . The said plunger-lever D^4 also operates the wad-winding-spindle stop-fingers $A^6 A^6$, before referred to, the said fingers being horizontally arranged and adjustably mounted in the upper ends of vertically-arranged arms $a' a'$, the lower ends of which are furnished with sleeves $a^2 a^2$, fitting over the ends of a rock-shaft a^3 , carrying an operating-finger a^4 , which extends forward and downward in position to be engaged by the upper edge of the lever D^4 , whereby the shaft is rocked. The said arms $a' a'$ have independent movement on the shaft, to which they are secured by means of pins $a^5 a^5$, passing through elongated slots a^6 , formed in the said sleeves. Springs $a^7 a^7$, connected with the upper ends of the arms, exert a constant effort to draw the arms, and hence the fingers, forward and engage the latter with the stop-cams $A^5 A^5$ at the upper ends of the wad-winding spindles $A A$. The lifting of the fin-

ger a^4 by the lifting of the forward end of the lever D^4 will cause the rock-shaft A^3 to be rocked rearward, whereby the fingers will be simultaneously disengaged from the two stop-cams; but the arms are free to be moved forward independent of each other by the springs $a^7 a^7$ within the limit of movement allowed by the length of the slots $a^6 a^6$, so that the fingers act independently in the performance of their stopping functions, and this is desirable because on account of variations in the thickness of the paper the wad-winding spindles will not stop simultaneously, from which it follows that the stop-cams $A^5 A^5$ at their upper ends will not come to rest in the same relative positions, so that if the arms $a' a'$ were rigidly connected to the rock-shaft a^3 , so as to maintain the fingers $A^6 A^6$ in fixed relations to each other, the engagement of one finger with a high point of the stop-cam with which it coacts might prevent the other finger from properly engaging with the stop-cam with which it coacts. From this it will be seen that it is essential that the two wad-winding-spindle stop-fingers should within narrow limits be free to be moved forward independent of each other by the springs $a^7 a^7$, so that they may be ready at all times to properly coact with the stop-cams without regard to the positions at which the same come to rest.

Only one of the wad-winding friction-belts A^4 is shown. That is seen in Fig. 1 to run over one of the wad-winding pulleys and over a driving-pulley a^8 , mounted on a driven shaft a^9 , supported at the upper end of a rearwardly-inclined arm a^{10} . An idler a^{11} rides upon the belt A^4 and keeps it taut, the said idler being mounted in the outer end of a swinging arm a^{12} , pivotally connected with the upper end of the arm a^{10} .

For the purpose of expanding the upper ends of the tubes preparatory to their reception of wads I preferably furnish the machine with two conical expanders $a^{13} a^{13}$, mounted in a cross-piece a^{14} , secured to the lower end of a vertically-arranged stem a^{15} , mounted with a capacity for vertical adjustment in a portion of the reciprocating plunger-head D^2 . With every descent of this head the conical expanders descend and enter the open upper ends of two tubes, which they expand into slightly bell-mouth shape. The use of these expanders is not imperative, although preferred.

It will be understood that in the operation of the wad-winding mechanism the paper is fed by the feed-rolls through the slots in the annular dies, and through the slots in the lower ends of the plungers, and through the slots in the lower ends of the wad-winding spindles. After the paper has been fed, as described, the rolls separate to permit the paper to be drawn freely between them thereafter by the action of the wad-winding spindles, which begin to rotate almost immediately after the paper has been fed, but be-

fore the spindles begin to rotate the plungers are raised so as to clear the lower ends of the spindles and leave the lower ends of the dies free for the formation of the wads.

By preference I slot the lower ends of the plungers and feed the paper when the plungers are depressed, as set forth, as I save time in that way, the paper being fed before the plungers have had time to retire after stripping the wads from the spindles, but the slotting of the plungers is not essential. After the paper has been fed, as described, and is released by the feed-rolls and the plungers have been elevated the stop-fingers are automatically disengaged from the stop-cams at the upper ends of the spindles, leaving the spindles free to be rotated with great rapidity by the friction-belts $A^4 A^4$. The spindles continue winding until the exterior peripheries of the wads engage with the inner peripheries of the annular dies and develop an amount of friction superior to the friction between the said belts and the grooved pulleys $A^3 A^3$, when the spindles come to a standstill. The reciprocating knives $H H$ are now operated for cutting off the wound wads from the strips. The plunger-head D^2 , carrying the plungers $D D$, now descends and the plungers strip the wads off from the spindles and force them out of the dies into shells $E^3 E^3$, which are presented under them. Meanwhile the stop-fingers have been allowed to drop into position to engage with the stop-cams of the spindles. As soon, then, as the spindles are relieved of the restraining action of the wads they are started in rotation again by their belts $A^4 A^4$, but this rotation is only partial, as they can be rotated no further than is required for the engagement of the shoulders of their stop-cams with the said fingers, which hold them against rotation and with the slots in their lower ends in right position for the reception of the free ends of the paper strips, at which time the said slots are aligned with the slots in the plungers and dies. The operation above referred to is then repeated, and so on.

By frictionally stopping the wads I am enabled to compensate for variations in the thickness of the paper, whereas if the spindles were rotated a predetermined number of times any want of uniformity in the paper could not well be compensated for and the wads might vary in size, but I do not limit myself to constructing the wad-winding mechanism so as to have the spindles stopped frictionally, as I might arrange the mechanism to stop them positively after a predetermined number of revolutions. It will be understood, however, that when the machine is constructed as shown and described for the frictional stoppage of the wads after they have attained full size the action of the stop-fingers is timed so that the equal periods between their automatic operation will always be long enough to permit a full-sized wad to be wound when the paper is running at its thinnest. In other words, the action of the

stop-fingers is timed so that there will always be a slight margin of time over and above the time required for the formation of a full-sized wad and its frictional stoppage, for 5 otherwise it might happen that the spindles would be automatically stopped before the wads were wound to full size, particularly in case the paper should run thin.

The assembling or cupping mechanism employed in my improved machine may be of any 10 approved construction. As herein shown, it employs a reducer I, a crimper I', an assembling-punch I², a seating-punch I³, and a take-off or stripper I⁴, the reducer I, crimper I', 15 assembling-punch I², and seating-punch I³ being all secured to the lower end of a gate-head I⁵, playing up and down in a suitable press-frame and actuated by an operating-lever I⁶, rocking on a stud I⁷ and having its 20 outer end connected with an eccentric-rod I⁸, the opposite end of which is connected with and driven by the main or driving shaft G', which is located directly below the driving-shaft G. The take-off I⁴ is mounted so as to 25 have vertical reciprocation in a box I^{4a}, secured to the gate-head, and is connected with the outer end of the lever I⁶, and thus has imparted to it a vertical reciprocating movement in addition to the movement which it 30 has with the gate-head I⁵ on account of its box I^{4a} being connected therewith. The function of the reducer is to reduce the shells to their normal size, or, in other words, to remove the expansion which they undergo under 35 the action of the conical expanders. The crimper crimps the upper ends of the shells and reduces them in size sufficiently to permit the ready application of the cups i, while the seating-punch I³ pushes the cups home 40 and seats them more solidly on the upper ends of the tubes than the assembling-punch.

The take-off I⁴ is of known construction and operates to strip the wadded and cupped tubes from the feeding mechanism and discharge them from the machine. In its descent with the gate-head the take-off is forced 45 down upon the cupped end of a shell, so as to grip the same. Then the supplemental movement imparted to the take-off on account 50 of its connection with the lever I⁶ causes it to be lifted independently of the gate-head, whereby the shell is stripped from the pin with which it is engaged. The next time the gate-head descends and the shell on the next 55 succeeding pin is stripped therefrom by the take-off the last shell lifts the preceding shell upward through the take-off, and so on, a column of loose shells being located in the take-off when the machine is operating and 60 one shell tumbling out of the upper end of the take-off for every revolution of the machine into a trough or other medium of discharge. It seems unnecessary for me to further describe the details of the take-off, as 65 the same is *per se* an old device. The cups i are fed downward under the assembling-punch I² by the action of gravity through a

chute or guideway J, the lower end of which is curved and terminates in two corresponding, horizontally-arranged, yielding cup-holding fingers J' J', having their forward ends bowed toward each other to prevent the forward lateral escape of the cups, the flanges of which rest upon the upper edges of the fingers, as shown in Fig. 12^a. The cups, being fed by gravity into the said fingers, are disengaged therefrom by the action of the assembling-punch which engages with the cups, causing the fingers to spread apart and permit the cups to pass down over the wadded upper ends of the paper tubes, as clearly shown in Fig. 12. The fingers J' J' may, however, be replaced by other means for presenting the cups to the tubes. A guide J^a is located below the said fingers, as shown in Fig. 12, and forms, as it were, an extension of the chute J. The cups are fed into the chute from a large flat hopper J² of any approved construction and do not need detailed description. By preference I shall employ an agitating device to insure the feeding of the cups into the chute from the hopper.

The feeding mechanism employed in my machine has the twofold function of presenting the empty tubes to the wadding mechanism and of presenting the wadded tubes to the assembling or cupping mechanism. A single feeding mechanism therefore suffices for both of the other mechanisms. As herein shown, this feeding mechanism consists of a horizontally-arranged dial K, mounted upon the bed K' of the machine and furnished with a circular series of corresponding pins K², adapted in diameter to firmly support the tubes, the lower ends of these pins being larger than their upper ends to form a shoulder K³ upon which the lower ends of the tubes rest. As herein shown, the dial is held down upon the bed K' and centered by means of a circular plate K⁴, which in turn is held down and centered by means of a disk K⁵, receiving the upper end of a bolt K⁶, which, through the medium of the disk K⁵ and plate K⁴, secures the dial to the bed. Springs K⁷ K⁸, interposed between the disk and plate, make the connection a yielding one. The dial is actuated intermittently or step by step through equally-spaced pins K⁸, located in its periphery and engaged by a pawl K⁹, pivotally mounted upon a lever K¹⁰, having its inner end hung upon the bolt K⁶ as a center and having its outer end connected by a yoke K¹¹, a rod K¹², and a yoke K¹³ with an eccentric K¹⁴, actuated by a cam, (not shown,) but mounted upon the driving-shaft G', as seen in Fig. 2, the said shaft being furnished with a driving-pulley K¹⁵ and driving the driven shaft through a gear-wheel K¹⁶, mounted thereupon.

The feeding mechanism shown and described may be replaced by other forms of feeding mechanism—such, for instance, as an endless belt; but whatever the form the feeding mechanism takes it will be constructed

and arranged to have the twofold function of presenting the empty tubes to the wadding mechanism and then presenting without intermediate handling the wadded tubes to the 5 assembling or cupping mechanism.

The operation of the several mechanisms has been so fully set forth in connection with their detailed description that it is thought unnecessary to describe or speak further of 10 the operation of the machine more than to say that, as herein shown, it is designed that the assembling mechanism shall be run twice as fast as the wadding mechanism. This is for the purpose of allowing ample time for 15 winding and solidifying the wads. The machine is therefore geared up to cause the dial of the feeding mechanism to make two movements to one movement of the plungers of the wadding mechanism, so that the wads are introduced 20 into the alternate tubes instead of into the successive tubes; but the tube that skips the first wad-winder will be filled by the second, and so on. The machine is also geared up, so that the cupping mechanism shall operate 25 at the same speed as the feeding mechanism.

The introduction of the wads into alternate tubes instead of into successive tubes results from the described mode of timing the operation 30 of the dial with respect to the operation of the wadding mechanism which is made double, so that it may be run only half as fast as the feeding mechanism, which is a single mechanism, and which, on account of 35 its character and function, may be safely run at twice the speed of the wadding mechanism.

It is not to be understood that the two wad-winders operate alternately, for their wad-winding action is simultaneous, so that although 40 the feeding mechanism runs twice as fast as the wadding mechanism the same is able to keep up with the feeding mechanism, because it contains two wad-winders, or, in other words, is a double mechanism.

In the operation of the machine the two plungers of the wadding mechanism descend simultaneously and wad two shells, the two plungers being separated so as to virtually straddle one shell, which will be left empty. 45 The next movement of the dial brings the empty shell under the inner plunger, the outer of the two shells previously wadded between the two plungers, and an empty shell under the outer plunger. Then the next time the two plungers descend they will wad the two empty shells mentioned and straddle, as it were, the wadded shell between them. As 50 two shells are wadded every time the plunger descends it is clear that the wadding mechanism has to run only half as fast as the feeding and cupping mechanisms need to run to keep up with it.

In view of the various changes and substitutions which have been suggested and others which may obviously be made I would have it understood that I do not limit myself 65 to the exact construction herein shown and

described, but hold myself at liberty to make such changes and alterations as fairly fall within the spirit and scope of my invention. 70

Having fully described my invention, what I claim as new, and desire to secure by Letters Patent, is—

1. In an automatic machine for wadding and cupping paper-shell cartridges, the combination with a wadding mechanism, of an assembling or cupping mechanism, a single feeding mechanism arranged with relation to the said wadding and cupping mechanisms so as to present empty paper tubes to the wadding mechanism in position to receive the wads produced thereby, and then to present the wadded tubes to the assembling or cupping mechanism in position to have cups applied to their wadded ends, whereby one feeding mechanism is adapted to feed not only a wadding mechanism, but also a cupping mechanism, and operating connections for driving the said wadding, cupping and feeding mechanisms, which are timed to perform their 90 functions in the right order.

2. In an automatic machine for wadding and cupping paper-shell cartridges, the combination with a double wadding mechanism, of a cupping mechanism, a feeding mechanism to present empty tubes to the wadding mechanism, and then to present the wadded tubes to the cupping mechanism, and operating connections whereby the feeding mechanism is operated at twice the speed of the 95 double wadding mechanism, and whereby the cupping mechanism is operated at the same speed as the feeding mechanism, substantially as described.

3. In an automatic machine for wadding and cupping paper-shell cartridges, the combination with a wadding mechanism, of an assembling or cupping mechanism, an intermittently-actuated dial adapted to receive empty tubes and arranged with reference to the said wadding and cupping mechanisms so as to present empty tubes to the former for the introduction of wads into them, and then to carry the wadded tubes on to the cupping mechanism for the application of cups 110 to them thereby, and means for operating the said wadding and cupping mechanisms and dial in proper concert, substantially as set forth, and whereby a single dial is made to perform the twofold office of feeding not only a 115 wadding mechanism, but also a cupping mechanism, without any intermediate handling of the shells.

4. In an automatic machine for winding wads, the combination with a wad-winding 125 spindle having its lower end slotted, of a pair of feed-rolls, one of which is positively moved toward and away from the other for causing them to grip and feed the paper to the spindle, and then release it to permit it to be drawn 130 inward by the spindle; a shaft upon which one of the rolls is mounted and the lower end of which is made elastic to permit its lateral deflection for enlarging the space between the

two rolls when the paper runs thicker than gage; and a bushing chambered for the reception of the elastic portion of the said shaft so as to give clearance thereto for the lateral 5 deflection thereof.

5. In a machine for winding wads, the combination with two wad-winding spindles having their lower ends slotted, of two pairs of feed-rolls of which each pair has one roll pos-
10 tively movable toward and away from its fellow for causing the rolls to temporarily grip the paper strips and feed them to the said spindles, and then release the paper strips to permit the same to be drawn inward by the
15 spindles; and means for connecting the movable rolls of each pair of rolls for their operation in unison, so that the two strips will be fed at the same time to their respective spindles, one roll of each pair of rolls being yield-
20 ing to provide extra space between the rolls in case the paper runs thicker than gage.

6. In an automatic machine for winding wads, the combination with two wad-winding spindles, of two pairs of feed-rolls, an eccentric bushing for one roll of each pair of rolls, and means for connecting the said eccentric bushings together so that the movable roll of each pair may simultaneously move toward and away from its fellow.

30 7. In a machine for winding wads, the combination with two wad-winding spindles having their lower ends slotted, of stop-cams mounted upon the said spindles, means for driving the said spindles simultaneously, a
35 rock-shaft, two arms carried thereby and mounted for independent oscillation thereupon, two stop-fingers respectively mounted

in the said arms and arranged to coact with the said stop-cams, and springs coacting with the said arms for the independent operation 40 of the stop-fingers within the limits of the independent movement of the said arms upon the rock-shaft, whereby the stop-fingers will be simultaneously disengaged from the two stop-cams, but independently reengaged 45 therewith by the said springs.

8. In an automatic machine for wadding and cupping paper-shell cartridges, the combination with a wadding mechanism, of an assembling or cupping mechanism, and a sin-
50 gle, feeding mechanism arranged with relation to the wadding and assembling mechanisms so as to present empty shells to the wadding mechanism in position to have wads introduced into them thereby, and then to carry 55 the wadded shells to the cupping mechanism and present them thereto in position to have cups applied to them thereby, the said cupping mechanism comprising an assembling-punch, a long chute down through which the 60 cups are fed by gravity, yielding fingers located at the lower end of the said chute for receiving cups therefrom and holding them under the punch, and a guide located below the said fingers and guiding the cups on their 65 way from the same into the said shells.

In testimony whereof I have signed this specification in the presence of two subscribing witnesses.

WILLIAM MASON.
